CORRUGATED HOSE

Joseph F. Bauman, Trenton, N.J., assignor to Acme-Hamilton Manufacturing Corporation, Trenton, N.J.

Filed Feb. 27, 1968, Ser. No. 10,746

Term of patent 14 years

Int. Cl. D23—01

U.S. Cl. D23—45

FIG. 1

FIG. 2

FIG. 3

FIG. 1 is a side elevational view of a corrugated hose showing my new design;

FIG. 2 is an end elevational view thereof; and

FIG. 3 is a sectional view taken on the line 3—3 of FIG. 1.

The dominant features of my design reside in the portions shown in full lines, it being understood that the center of the corrugated hose is broken away in FIG. 1 to indicate indeterminate length.

I claim:

The ornamental design for a corrugated hose, substantially as shown and described.
